UNITED STATES PATENT OFFICE

MAYNARD ROSENBERGER, OF LOS ANGELES, CALIFORNIA, ASSIGNOR TO ADOHR STOCK FARMS, OF RESEDA, CALIFORNIA, A CORPORATION OF CALIFORNIA

DESIGN FOR A BOTTLE

Application filed June 8, 1931. Serial No. 40,119. Term of patent 14 years.

To all whom it may concern:

Be it known that I, MAYNARD ROSENBERGER, a citizen of the United States, residing at Los Angeles, in the county of Los Angeles and State of California, have invented a new, original, and ornamental Design for Bottles, of which the following is a specification, reference being had to the accompanying drawings forming a part thereof.

Fig. 1 discloses an elevational view of a bottle, and

Fig. 2 is a plan view thereof, showing my new design.

I claim:

The ornamental design for a bottle, as shown.

Signed at Los Angeles, Calif., this 22nd day of May, 1931.

MAYNARD ROSENBERGER.
